FOOD WARMER

Angelo C. Scavullo, Jamaica, N.Y., assignor to Legion Utensils Co., Inc., a corporation of New York

Filed Apr. 24, 1958, Ser. No. 50,607

Term of patent 14 years

(Cl. D81—10)

FIG. 3

Fig. 1 is a top perspective of a food warmer, showing my new design;

Fig. 2 is a side elevational view thereof; and

Fig. 3 is an elevational end view thereof; the opposite end being a mirror image thereof. The rear of the shield member is plain.

I claim:

The ornamental design for a food warmer, as shown and described.
